UNITED STATES PATENT OFFICE.

EMORY GLENN SIMPSON, OF DETROIT, MICHIGAN, ASSIGNOR TO FISHER BODY CORPORATION, OF DETROIT, MICHIGAN, A CORPORATION OF NEW YORK.

WIRE-WINDING MACHINE.

1,278,043.

Specification of Letters Patent. Patented Sept. 3, 1918.

Application filed November 26, 1917. Serial No. 203,895.

To all whom it may concern:

Be it known that I, EMORY GLENN SIMPSON, a citizen of the United States, residing at Detroit, in the county of Wayne, State of Michigan, have invented a new and useful Improvement in Wire-Winding Machines, of which the following is a specification.

This invention relates to machines for winding wire about loops, and is especially intended for winding the ends of a loop in a stay wire for aeroplanes.

The features of construction and the novel parts will appear in the more detailed description following.

In the drawings,—

Figure 1 is a longitudinal section of the machine partly in elevation.

Fig. 2 is a plan view.

Fig. 3 is a cross section on the line C—C of Fig. 1.

Fig. 4 is a cross section of the loop-holder in closed position.

Fig. 5 shows the same part in open position.

The frame of the machine is designated *a* and has a head *b* provided with an opening adapted to take the sleeve *c* which is secured in position by the set screw *d*. This sleeve *c* performs the double function of acting as a bearing shaft and a socket for the removable loop-holder *e*. The loop-holder *e* is a split cylindrical member whose construction will be better understood by referring to Figs. 4 and 5. This comprises two parts of a cylinder hinged together by the knuckles *f* and the knuckle pin *g*. At the center of the cylinder the two-part cylinders do not quite meet by a space sufficient to hold the two ends of a wire loop. The consequence is that when the cylindrical holder is opened up, as shown in Fig. 5, the wire looped back upon itself may be inserted by laying it in the opened cylinder.

The cylinder may be closed up as shown in Fig. 4, leaving the loop portion of the wire exposed as shown in Fig. 1 at the end of the cylinder. Pressure pins *h* operated by coil springs serve to afford a friction on the looped ends of the wire so as to hold the same frictionally. Obviously when the two-part cylinder is inserted in the socket formed by the sleeve *c*, this serves to hold the two parts together.

On the outside of the sleeve *c* is journaled

the rotating head *i* with an interposed bronze bushing *j*. This rotating head has external gear teeth *k* which mesh with the gear teeth on the driving gear *l* attached to the driving shaft *m* which is driven by a pulley *n* and connected with this pulley by means of the clutch *o*.

This rotating head carries a spool-holding stud *p* upon which is adapted to be rotatably mounted the spool of wire *q*. A tension device is located on the head opposite the spool-holding stud and comprises simply a segmental block *r* with a circumferential groove, around which and in which lies the wire to be fed on to the work. The pivoted bar *t* has a foot *u* adapted to press against the wire that lies in the circumferential groove. This foot *u* is urged against the wire by means of the tractile spring *v* whose tension may be adjusted by turning the screw *x* so as to lengthen or shorten the spring. Obviously by lengthening the spring the pressure on the wire is greater and consequently the tension greater between the tension block and the loop or work.

When the machine is set into operation by shifting the clutch lever *w*, the wire spool and tension device are caused to rotate about the stationary loop-container and consequently winds the wire upon the loop, but this winding would be a mere piling up were it not for the fact that the work is advanced just the proper distance continuously to make the wind a true and tight spiral. This advance of the work is secured by connecting the power shaft and threaded shaft *y* by means of a properly calculated reduction gearing *z*. A slide 1 traveling longitudinally of the machine in a slide-way has a liftable half nut connection 2 with the threaded shaft; hence the slide being constrained from rotation and the threaded shaft engaging with the nut, rotation of the shaft causes the slide to travel away from the stationary head *b* of the machine. A hook 3 is carried by the top of the slide and is adapted to be hooked into the looped work. Consequently when the rotating head begins to rotate the work simultaneously begins to travel away from the stationary head at just the right pace to form a true but tight spiral.

The stem 4 rises from the half nut 2 and the nut may be lifted off from the threads of

the shaft y by means of the lever 5. The compression spring 6, however, normally tends to keep the half nut in engagement with the threads.

- 5 By the machine here described, loop ends may be bound together and their windings machine laid, as distinguished from what has been the practice heretofore to wind these by hand. The prior practice has been 10 hard, slow and less satisfactory work than is performed by this machine.

What I claim is:

1. In a machine for the purpose specified, a stationary head, a sleeve secured therein, a 15 rotating head journaled on the outside of the sleeve and provided with a spool-carrying stud, a work-carrying cylinder insertible in the interior of the sleeve, and means for advancing the work contemporaneously with 20 the winding of a linear member from off the spool on to the work.
2. In a machine for the purpose specified, the combination of a stationary head, a rotating head journaled about the stationary 25 head, and a loop-holding cylinder insertible in a cylindrical socket of the stationary head and comprising a pair of part cylinders hinged together and adapted to pinch the ends of the loop between the same.
- 30 3. In a machine for the purpose specified, a stationary head, a rotating head journaled about the stationary head and having a

spool-carrying member and a loop-holding member insertible in a socket in the stationary head axially of the rotating head and comprising a pair of cylinder parts hinged 35 together.

4. In a machine for the purpose specified, a stationary head, a rotating head provided with a spool-carrying device and journaled 40 about the stationary head, and a loop-holding cylinder insertible in a socket in the stationary head axially of the rotating head and comprising a pair of part cylinders 45 adapted to engage the loop ends between them and containing one or more presser pins for frictionally engaging the loop ends.

5. In a machine for the purpose specified, a stationary head, a rotating head provided with a spool-carrying device and journaled 50 about the stationary head, a loop-holding cylinder insertible in a socket in the stationary head axially of the rotating head and comprising a pair of part cylinders adapted to engage the loop ends between them and 55 containing one or more presser pins for frictionally engaging the loop ends, and means for engaging in the end of the loop and advancing the same with respect to the loop-carrier against the friction produced by the 60 presser pin or pins.

In witness whereof I have hereunto set my hand on the 15th day of November, 1917.

EMORY GLENN SIMPSON.
